APPARATUS FOR CORRUGATING SHEET METAL RECEPTACLES

Original Filed July 24, 1933 2 Sheets-Sheet 2

UNITED STATES PATENT OFFICE

2,017,574

APPARATUS FOR CORRUGATING SHEET METAL RECEPTACLES

Jacques Stanitz, Warren, Ohio, and George D. Boyer, deceased, late of Warren, Ohio, by Clara M. Boyer, Warren, Ohio, and the McDowell National Bank, Sharon, Pa., executors, assignors to The Youngstown Pressed Steel Company, Warren, Ohio, a corporation of Ohio

Original application July 24, 1933, Serial No. 681,833, now Patent 2,003,981, June 4, 1935. Divided and this application May 2, 1935, Serial No. 19,472

6 Claims. (Cl. 153—70)

The invention relates to apparatus for corrugating sheet metal receptacles and more particularly, the invention relates to apparatus for forming a series of grooves, channels, furrows, flutes, and the like to produce ribs, corrugations, and the like, extending upwards in the side walls of relatively deep receptacles or containers drawn or formed from a single piece or blank of sheet or plate metal.

10 Such receptacles may be used for many purposes, for example, as tubs for power-driven washing machines; and it is desired that such corrugated receptacles have grooves, and the like, preferably of uniform width, depth and contour throughout their extent, and/or that the grooves, and the like extend upwards in the side walls of the receptacles from an intermediate portion of a curved corner wall provided between the integral bottom and side walls thereof.

20 It is therefore a principal object of the present invention to provide apparatus for making and corrugating sheet metal receptacles having the characteristics just described, in which grooves, channels, furrows, flutes, and the like, are provided in the receptacle side walls extending upwards therein from a preferably intermediate portion of the curved corner wall provided between the integral receptacle bottom and side walls.

30 Different ways have been proposed and used for forming corrugated side walls for sheet metal receptacles made from integral sheet blanks, but the same have either involved the formation of tapered corrugations in the side walls which extend completely to the top edge of the receptacles, or have involved the formation of usually quite shallow corrugations extending only in portions of the side walls and which do not extend upwards from an intermediate portion of a curved corner wall between integral receptacle side and bottom walls.

40 Another method of making sheet metal receptacles has been proposed in which a bottom wall is seamed or otherwise joined to separately made, formed and corrugated sheet metal side walls.

45 However, the receptacles which are produced in such ways are not satisfactory for the purposes which are admirably satisfied by our improved products; apparatus for making which comprises another of the objects of the present invention.

50 It has been proposed that substantially vertical corrugations may be formed in the side walls of a sheet metal receptacle drawn from a single sheet or blank of metal by circumferentially rolling the side walls between corrugating

rolls having axially extending corrugations in their outer surface; or by stamping or pressing one or more corrugations successively around the periphery of the side walls of a receptacle.

5 However, such ways of making corrugated receptacles have proven unsuccessful because the corrugations provided thereby have full depth only for a portion of their extent, and the corrugations become shallow in other portions thereof. Moreover, the receptacle side walls are gathered or bulged inward so that a generally cylindrical outside receptacle contour cannot be maintained, because only one or relatively few corrugations are formed at any one time in the side walls by such methods and the side wall 10 metal is thereby gathered, rather than being stretched by the corrugating operation.

20 It has also been attempted to provide corrugations in the side walls of a deep drawn receptacle having an integral bottom wall by utilizing a punch cooperating with a female die having inwardly protruding die ribs provided with a contour in cross section corresponding to the contour of grooves desired to be provided in the receptacle side walls. However, the formation of ribs in the 25 side walls of a receptacle by these means, even though the die ribs or bars are polished or formed from specially plated metal or from tool steel, produces scratches in the receptacle side walls where the corrugations are formed, so that the 30 same are absolutely unsatisfactory and cannot be provided with a vitreous enamel coating, which in many cases it is desired to provide on the receptacles which the present invention proposes to make.

35 It is therefore a further object of the present invention to provide apparatus for making and corrugating the side walls of a deep drawn sheet metal receptacle which avoids all these difficulties and by which sheet metal receptacles having 40 corrugated side walls may be satisfactorily made with resulting truly vertically extending side walls and which may be provided with a vitreous enamelled coating.

45 It is likewise a further object of the present invention to provide apparatus for making and corrugating the side walls of a deep drawn sheet metal receptacle by which either vertically or spirally extending grooves of either equal or varying length may be provided in the receptacle side 50 walls.

When sheet metal receptacles having integral side and bottom walls are utilized as tubs for washing machines, it is desirable in many cases to provide special formations in the tub bottom 55

wall for drainage purposes, and/or to offset portions of the bottom wall from the remainder thereof, which bottom wall formations may be readily made during the receptacle drawing operation prior to corrugating the side walls.

It is therefore a further object of the present invention to provide apparatus for making and corrugating the side walls of a deep drawn sheet metal receptacle which when used for carrying out the corrugating operation will not distort bottom wall formations which may have been provided in the receptacle bottom wall when the receptacle blank is drawn.

And finally, it is an object of the present invention to provide apparatus for making and corrugating the side walls of a deep drawn sheet metal receptacle which satisfies the desiderata described above, which may be operated in an inexpensive manner, and which may be used to produce corrugated sheet metal receptacles having pleasing, attractive and distinctive appearances.

These and other objects may be obtained by the apparatus, combinations, sub-combinations, parts and elements, preferred embodiments of which are shown in the accompanying drawings, in which:—

Figure 1 is a view of a deep drawn receptacle blank having integral bottom and side walls with a curved corner wall therebetween, prior to being operated upon by the improved apparatus;

Fig. 2 is a view of the receptacle blank after the improved apparatus has been used to provide the same with grooves extending upwards in its side walls from an intermediate portion of the curved corner wall;

Fig. 3 is an axial sectional view through the improved apparatus, which may be used to form the corrugated receptacle shown in Fig. 2 from the deep drawn receptacle blank shown in Fig. 1;

Fig. 4 is an enlarged fragmentary sectional view of portions of the die means shown in Fig. 3;

Fig. 5 is a fragmentary sectional view taken on the line 5—5, Fig. 4;

Fig. 6 is a view similar to Fig. 1 of a deep drawn receptacle blank;

Fig. 7 is a view similar to Fig. 2 of a corrugated receptacle made from the blank shown in Fig. 6 having a modified form of side wall corrugations;

Fig. 8 is a view similar to Fig. 3, of the die means shown in Fig. 3 slightly modified to form the receptacle corrugations shown in Fig. 7;

Fig. 9 is an enlarged fragmentary sectional view similar to Fig. 4 of the die means shown in Fig. 8; and

Fig. 10 is a fragmentary sectional view similar to Fig. 5, taken on the line 10—10, Fig. 9.

Similar numerals refer to similar parts throughout the various figures of the drawings.

A receptacle blank indicated generally at 11 in Fig. 1 is formed from a single piece of sheet or plate metal to provide a bottom wall 12, side walls 13 integral therewith, and with a curved corner wall 14 therebetween, in suitable dies. The blank

11 may then be provided with spaced grooves, channels, flutes, furrows and the like, indicated at 15 in Fig. 2 in the side walls 13 thereof extending upwards in the side walls preferably from an intermediate portion 35 of the curved corner wall 14 to form the corrugated receptacle generally indicated at 16 in Fig. 2, by utilizing the improved apparatus.

One form of the improved apparatus is shown in Figs. 3, 4 and 5, and may comprise a male die 17, mounted in any usual manner on a press ram

head 18, and a female die generally indicated at 19, mounted on the press base 20, the male and female dies 17 and 19 being relatively axially movable.

As shown in the drawings, the female die 19 may be provided with a series of removable rings 21 provided with a series of spaced axially extending grooves 22, a ring plate 23 being interposed between each ring 20 for a purpose which will be hereinafter described.

The upper portion of the female die 19 may also be provided with a recessed ring plate 24, and a ring 25 provided with a series of grooves 26 for a purpose which will also be hereinafter described. Clamping air cushioning means may also be provided, including a clamping head 27, which may cooperate with the lower end of the male die 17, to clamp the receptacle blank 13 thereto; the clamping head 27 being mounted on piston rods 28 extending from an air cylinder 29, and the like.

A series of spherical balls 30 are located in each of the grooves 22 of each removable ring 21; and a series of grooves 31 is provided in the outer cylindrical surface 32 of the male die 17 corresponding in number and location to the grooves 22 with balls 30 therein of the female die 19.

The male die 17 may also be provided with a removable bottom plate 33 and the clamping head 27 may be provided with a removable top plate 34 for a purpose which will be hereinafter described.

In utilizing the improved apparatus, a single piece of sheet or plate metal is first drawn to form a receptacle blank 11 with integral side walls 13 and bottom wall 12, and with a curved corner wall 14 therebetween. The side walls 13 of the receptacle blank 11 are preferably formed to be cylindrical, while the bottom wall 12 thereof may have any desired formation, for providing for drainage and the like, as by offsetting a portion of the bottom wall from the remainder thereof.

The receptacle blank 11 is then telescoped upon the grooved male die 17, which has outer bounding surfaces conforming to the inner surfaces of the receptacle blank, the removable bottom plate 33 thereof having a shape corresponding to the shape or inner contour of the bottom wall of the receptacle blank 11.

The clamping air cushioning means is then operated to move the clamping head 27 against the bottom wall of the receptacle blank, so as to clamp the receptacle blank against the male die 17; the removable clamping head top plate 34 having a contour corresponding to the outer contour or shape of the formed receptacle bottom wall.

The purpose of clamping the bottom wall of the receptacle blank to the male die 17 is to hold the bottom wall shape in the manner in which it was formed during the drawing operation, so that it will not be pulled out of shape when the side walls 13 are being corrugated.

The removable parts 33 and 34 are provided so that different ones may be readily connected to the die 17 and clamping head 27 to accommodate receptacle blanks having different bottom wall formations.

The male and female dies 17 and 19 are then relatively axially telescoped as by moving the press ram head 18 downward so that the receptacle blank 11 on the male die 17 is forced into the female die 19 in the manner best illustrated in Fig. 4 of the drawings, whereby the rolling die 75

means or balls 30, which correspond in contour substantially to the contour of the grooves 31 in the male die 17, form grooves 15 in the blank side walls progressively upwards from a portion 35 of a curved corner wall 14 of the receptacle blank 11.

The male die 17 is then withdrawn from the female die 19 and the resulting corrugated receptacle 16 may then be stripped from the male die.

The corrugated receptacle product 16 illustrated and described, but not claimed herein, is illustrated, described and claimed in the copending application of Jacques Stanitz and George D. Boyer, entitled Sheet metal receptacles, filed July 24, 1933, Serial No. 681,832, matured on June 18, 1935, as Patent No. 2,005,641.

Moreover, the apparatus disclosed, described and claimed herein constitutes improvements upon the apparatus shown, described and claimed in the Stanitz & Boyer Patent No. 1,919,869, dated July 25, 1933, entitled Corrugating apparatus.

And finally, this application is a division of the application of Jacques Stanitz and George D. Boyer, filed July 24, 1933, Serial No. 681,833, matured on June 4, 1935, as Patent No. 2,003,981, entitled Method of corrugating sheet metal receptacles, which discloses and describes, but does not claim the apparatus claimed herein.

The plates 23 are interposed between the rings 21 so as to relieve excessive pressure upon the lower balls of each series of balls 30 in each groove 22 of each ring 21. Moreover, certain of the upper balls 30 in the grooves of certain of the upper rings 21 may be removed in stepped relation around the periphery of the female die 19 if it is desired to form corrugations of varying lengths in the side walls of the receptacle extending from a portion of the curved corner wall thereof; such products being illustrated in said application entitled Sheet metal receptacles, filed July 24, 1933, Serial No. 681,832, matured on June 18, 1935, as Patent No. 2,005,641.

Moreover, if it is desired to form spiral grooves in the receptacle side walls instead of vertically extending ones as illustrated, the same may be accomplished by relatively rotating the male and female dies at the same time that the male and female dies are being relatively telescoped, as shown in Patent No. 1,919,869.

The balls 30 being rolling die means, cause the grooves or corrugations 15 to have a uniform depth, width and contour in cross section throughout their length; it being clear that if it is desired to make the grooves 15 deeper adjacent the bottom portion of the receptacle, than at the upper ends of the grooves, the same may be accomplished by providing larger balls 30 in the lower rings 23 of the female die, a corresponding provision being made in the grooves 31 of the male die 17.

In this manner, spaced relatively deep grooves may be formed in accordance with the improved method which extend upwards from a portion of the curved corner wall of a receptacle having integral bottom and side walls, as best shown in Fig. 4; and since the grooves are rolled in the side walls, no scratches are made in the receptacle side walls during the corrugating operation, which would prevent an unsatisfactory enamel coating from being applied to the receptacle.

Figs. 6 and 7 illustrate steps in the manufacture of another form of receptacle side wall grooves, the receptacle blank 11 shown in Fig. 6, being formed from a single piece of sheet or

plate metal with a bottom wall 12, side walls 13 integral therewith and a curved corner wall 14 therebetween. The blank 11 may then be provided with spaced grooves generally indicated at 15a each comprising preferably substantially flattened portions 15b and a curved portion 15c, the grooves 15a extending upwards in the side walls preferably from an intermediate portion 35a of the curved corner wall 14 to form the corrugated receptacle generally indicated at 16a in Fig. 7.

The manufacture of the receptacle 16a may be accomplished in the improved apparatus such as shown in Figs. 8, 9 and 10, which is a slightly modified form of apparatus shown in Figs. 3, 4 and 5, as by utilizing a male die 17a having grooves 31a therein corresponding with the shape of the grooves 15a to be provided in the receptacle 16a.

Likewise, the female die 19 is modified by removing the balls 30 and placing rollers 30a having substantially cylindrical portions 30b, spherical ends 30c and an intermediate enlarged portion 30d, in the grooves 26 of the ring 25 mounted above the ball rings 21.

The ring plate 24 is recessed at 24a to accommodate the enlarged portion 30d of each roller 30a; and the top member 36 of the female die 19 is also recessed at 37 adjacent each groove 26 to accommodate the enlarged portion 30d of each roll 30a. The apparatus shown in Figs. 8, 9 and 10 is operated to force the receptacle blank 11 into the female die 19 so that the rolls 30a form corrugations 15a in the side walls 13 thereof extending upwards from an intermediate portion 35a of the curved corner wall 14, as best shown in Fig. 9.

It is not intended to limit the scope of the present invention to the particular shapes of groove formations shown or described herein, because it is clear that other groove formations may be made on the improved apparatus by utilizing rolling die means having the desired shape.

Nor is it intended to limit the scope of the present invention to apparatus for making receptacles used solely as tubs for washing machines, because it is clear that other vessels or containers having corrugated side walls may be made on the improved apparatus, so that the term "receptacle" utilized herein and in the claims, is intended to include such articles.

Likewise, the word "grooves" used herein is intended to include grooves, channels, furrows, flutes and the like, which form ribs, corrugations and the like in the side walls of sheet metal receptacles; and the word "curved" utilized herein as describing the receptacle corner wall is intended to refer to any type of shaped or rounded corner as distinguished from one which is sharp.

And finally, the term "sheet metal" used herein and in the appended claims is intended to refer to sheet or plate metal according to the desired thickness of the material utilized.

The improved apparatus therefore provides for the inexpensive manufacture of attractive and distinctively appearing sheet metal receptacles having integral bottom and side walls from a single piece of sheet metal having a series of grooves forming ribs extending upwards in the side walls of the receptacles, preferably from an intermediate portion of a curved corner wall provided between the bottom and side walls, with

out there being any resulting annular recess present in the receptacles below the lower ends of the ribs or corrugations, and without so injuring the receptacles that they may not be satisfactorily coated with a uniform vitreous enamel coating.

We claim:—

1. Apparatus for forming grooves in the side walls of sheet metal receptacles, including a female die provided with a series of removable rings each having spaced inner axially extending grooves, a ring plate interposed between adjacent rings, and rotatable members in each of the grooves of certain of said rings, the lowermost rotatable member in each groove resting on the ring plate next below; and a male die adapted to be relatively telescoped within said female die having a series of grooves adapted to register with said rotatable members.
2. Apparatus for forming grooves in the side walls of sheet metal receptacles, including a female die provided with a series of removable rings each having spaced inner axially extending grooves, a ring plate interposed between adjacent rings, a plurality of rotatable members in certain of said grooves, the lowermost rotatable member in each groove resting on the ring plate next below; and a male die adapted to be relatively telescoped within said female die having a series of grooves adapted to register with said rotatable members.
3. In apparatus for forming grooves in the side walls of sheet metal receptacles, a female die provided with a series of removable rings each having spaced inner axially extending grooves, rotatable members in certain of said grooves, and a removable ring plate disposed below each of said rings and between adjacent rings, whereby said ring plates may support rotatable members placed in any of said grooves of any of said rings.
4. Apparatus for forming grooves in the side walls of a sheet metal receptacle having a bottom wall formed with an offset portion, including a female die provided with a series of removable rings each having spaced inner axially extending grooves, a removable ring plate disposed below each of said rings and interposed between adjacent rings, rotatable members in certain of said grooves, the lowermost rotatable member in each groove resting on the ring plate next below; a male die adapted to be relatively telescoped within said female die having a series of grooves adapted to register with said rotatable member, a removable bottom plate on said male die, a cushioned clamping head adapted to cooperate with the male die having a removable

top plate, and said bottom and top plates being formed with a contour corresponding to the contour of the formed receptacle bottom wall; whereby a receptacle may be securely clamped and held to the male die as the male die is being telescoped into the female die to form grooves in the side walls thereof.

5. Apparatus for forming grooves in the side walls of a sheet metal receptacle having a bottom wall formed with an offset portion, including a female die provided with a removable ring having spaced inner axially extending grooves, a removable ring plate disposed below said ring, a rotatable member in each of said grooves resting on the ring plate; a male die adapted to be relatively telescoped within said female die having a series of grooves adapted to register with said rotatable member, a removable bottom plate on said male die, a cushioned clamping head adapted to cooperate with the male die having a removable top plate, and said bottom and top plates being formed with a contour corresponding to the contour of the formed receptacle bottom wall; whereby a receptacle may be securely clamped and held to the male die as the male die is being telescoped into the female die to form grooves in the side wall thereof.

6. Apparatus for forming grooves in the side walls of a sheet metal receptacle having a bottom wall formed with an offset portion, including a female die provided with a series of removable rings each having spaced inner axially extending grooves, a removable ring plate disposed below each of said rings and interposed between adjacent rings, the lowermost rotatable member in each groove resting on the ring plate next below; a male die adapted to be relatively telescoped within said female die having a series of grooves adapted to register with said rotatable member, a cushioned clamping head adapted to cooperate with the male die, and the bottom wall of said male die and the top wall of said clamping head being formed with a contour corresponding to the contour of the formed receptacle bottom wall; whereby a receptacle may be securely clamped and held to the male die as the male die is being telescoped into the female die to form grooves in the side walls thereof.
